UNITED STATES PATENT OFFICE.

JOSEPH A. HOLMES, OF GREENLAND, NEW HAMPSHIRE.

ELEVATOR-BUCKET.

SPECIFICATION forming part of Letters Patent No. 296,008, dated April 1, 1884.

Application filed February 27, 1884. (No model.)

To all whom it may concern:

Be it known that I, JOSEPH A. HOLMES, of Greenland, in the county of Rockingham, in the State of New Hampshire, have invented a new and useful Improvement in Elevator-Buckets, of which the following is a full, clear, and exact description.

This invention, like that for which Letters Patent No. 290,053 were issued to me December 11, 1883, relates to belt or band elevators such as are used in mills for raising meal, grain, and other substances from one floor or story to another by means of buckets arranged at suitable distances apart on the band.

15 The invention described in my patent above referred to consists in a bucket open at its bottom, also at its top and mouth or delivery end, but having raised sides and back, said bucket being arranged so that the endless band 20 which carried it formed an inclosure or covering to the open bottom of the bucket. Buckets so constructed and combined with the band have the advantage of being much lighter than buckets having bottoms of their own. 25 The same also have a much quicker emptying action and admit of the band being run in a nearly vertical course, and do not clog with or carry around a second time the substance being raised. They likewise are cheap, durable, and strong, and, being secured on the outside of the band, they are capable of being readily removed or applied, as required. The bucket shown in the accompanying drawings 30 is similar in all the respects hereinbefore named to my patented bucket referred to, and possesses all the merits of it; but instead of being attached at its back or in its rear to the endless band, which answers every purpose for buckets of a certain size, I construct the 35 bucket so that provision is made for attaching it at or near the center of its length or sides to the endless band. This construction and attachment will prevent the buckets, when of a large size or heavily laden, from pulling 40 away from the band during the lift of the buckets.

Reference is to be had to the accompanying drawings, forming a part of this specification, in which similar letters of reference indicate 45 corresponding parts in both the figures.

Figure 1 represents a vertical section of an

endless belt and bucket elevator in part, having my improvement applied; and Fig. 2, a view, as seen from its under side, of one of the buckets detached.

55 A indicates the top drum or wheel, in part, of an endless belt and bucket elevator; B, its endless band or belt, in part, traveling as indicated by the arrow *a* in Fig. 1; and C C, certain of its several buckets open at their bottoms, tops, and mouths, and having their open bottoms closed or covered by the band, to the outside of which the buckets, constructed with a back, *b*, and raised sides *c c*, are attached. These buckets, instead of being secured at 60 their backs or in rear thereof to the band, are fastened at or about the center of their length or sides thereto—as, for instance, by flanges or 65 projections *e e* on the inner faces of the sides of the bucket in proximity to the band, and short bolts *d d*, arranged to pass through said flanges and the band. Thus secured at or 70 about their centers to the band, said buckets, when of a large size or heavily laden, will not, in rising with their load, pull away from the 75 band, as they sometimes are liable to do when secured in rear of their backs to the band. This is important, considering that the band constitutes the bottoms of the buckets.

Having thus described my invention, I claim 80 as new and desire to secure by Letters Patent—

1. In buckets of endless belt or band elevators, having open bottoms and raised sides and back, the bucket constructed or provided with means for attaching it in front of its 85 back, at or near the center of the length of its sides, to the exterior of the band, substantially as and for the purpose herein set forth.

2. In endless belt and bucket elevators, the combination, with the endless belt B, of the 90 buckets C, constructed with a back, *b*, and sides *c c*, but left open at their tops, bottoms, and mouths or delivery ends, and attached at or near the center of the length of their sides, in front of their backs, to the outside of the 95 belt or band, substantially as shown and described.

JOSEPH A. HOLMES.
